UNITED STATES PATENT OFFICE.

DAVID COCKBURN AND DONALD MACNICOLL, OF CARDONALD, NEAR GLASGOW, SCOTLAND, ASSIGNORS TO JOHN LLOYD TAYLOR AND ALBERT EDWARD TAYLOR, BOTH OF LIVERPOOL, ENGLAND.

ENGINE AND LIKE GOVERNOR.

1,331,416.

Specification of Letters Patent.

Patented Feb. 17, 1920.

Application filed April 15, 1919. Serial No. 290,341.

To all whom it may concern:

Be it known that we, DAVID COCKBURN and DONALD MACNICOLL, subjects of the King of England, and residing at Cardonald, near Glasgow, in the county of Lanark, Scotland, United Kingdom of Great Britain, have invented Improvements in or Connected with Engines and like Governors, of which the following is a specification.

10 This invention has reference to the system of controlling steam engines, in which a governor driven by the engine, is through the intermediary of a transmission medium caused to operate a controlling valve, say on 15 the steam supply or other motive fluid, whereby such valve is operated and closed, or governed, when an excessive speed is obtained, the valve in question being the ordinary throttle valve, or a special emergency 20 valve and gear.

According to this invention, between the governor and a valve controlled or operated thereby, and the steam or motive fluid controlling valve, controlling the supply of the 25 fluid to the engine, there is employed a fluid pressure motion system through which a fluid under pressure is either excluded from, or admitted to the system between the governor control valve, and the pressure fluid 30 main controlling valve, so that the pressure when supplied to the system, through suitable mechanism, operates upon excessive speed of the engine, to close the supply of pressure, to reduce the speed of the engine, 35 that is the system is normally closed when the speed of the engine and governor is not excessive, and kept closed (say by a spring), whereas when the speed is excessive it is opened, and so admits fluid under pressure 40 from a suitable source to the fluid pressure system, between the governor controlled or actuated valve, and the main engine motor fluid controlling valve.

In the accompanying drawings, this system 45 is illustrated, and several modifications of forms of governor control, and mechanisms controlled by it are given, and the invention will be further described in connection with these drawings.

50 Figure 1 of the drawings illustrates diagrammatically the system, and Fig. 2 shows in detail a construction of governor and valve actuated or controlled by it.

Fig. 3 shows a modified arrangement of the governor controlled or actuated valve 55 shown in Fig. 2.

Referring in the first instance to Fig. 1, 1 generally designates the governor; 2 a lever or arm operated by it; 3 the valvular device operated by the lever or arm; 4 the pipes of the fluid pressure system; and 5 the valvular controlling apparatus actuated or controlled by the governor.

In this system upon the governor attaining an excessive speed, the valvular apparatus 65 3 is operated, and the valve proper in it is opened so as to admit pressure fluid existing in the pipe 6, (which is connected with the source of fluid pressure supply) to act upon the fluid in the pipes 4, and this 70 pressure is conducted to a cylinder and piston, or other equivalent mechanism 7, which it operates; and operating upon a lever 8, through a relay say of any known suitable kind, actuates and closes the main engine 75 steam or motor fluid supply pipe or conduit, and so stops the engine.

In the case shown, this lever 8 of the valvular relay apparatus is also adapted to be operated by hand through the lever 9 working over a quadrant 10, and the short arm of which is connected by a connection 11 with the lever 8.

Referring now to the governor construction shown in Fig. 2, the governor which 85 acts upon the lever 2 comprises a stationary casing or cylinder 15, and a rotary part 16 revolved by the engine, having within it a body 17 mounted and adapted to slide radially in the cylindrical body 16 in a sleeve 90 18 therein; the body 17 being normally pulled inward in the rotatable carrier 16 by a spring 19, connected to it at one end, and at the other end fixed to the bottom 20 of the sleeve 18.

95 The inner portion of the lever 2 normally lies close to the rotary body 16; and when an excessive speed of the governor takes place, the body 17 moves readily out of the sleeve 18, and strikes on the inner edge of 100 the lever 2 (which is pivoted to the case 15) and moves it.

The valve actuated by the governor or lever 2 is marked 21, and it controls an opening in the wall 22 between the pressure 105 supply conduit 6, and the conduit 4; and

in the upper part of the casing of the valve 21, to which the pipe 4 is connected, is a non-return valve 23, which normally rests upon its seat in the case, but is lifted when 5 the fluid pressure is admitted to it by the pressing of the valve 21 off its seat.

The stem 24 of the valve 21 at its upper end, slides in a sleeve 25, which is normally pressed down by a spring 26, held at its 10 upper end in the casing 27, and at its lower end rests on a ring on the lower part of the sleeve 25, so that the spring urges the sleeve 25 in the direction of the opening of the valve 21.

15 The inner lower end of the sleeve 25 is adapted to act on the shoulder formed on the valve stem 24 just beneath it; and also in connection with a seating 28 in the casing 27, so that when the plunger is moved down, and the valve opened (the plunger resting on the seating 28, which is provided with a jointing material), the escape of pressure fluid along the valve stem 24, and thence from the valve casing 27, is prevented.

20 Within the sleeve 25 there is a second spring 30, which is held at its lower end by an internal flange on the sleeve, and at its other end acts on a shoulder formed by the enlarged head 31 of the valve stem 24, so that this valve stem is always pressed upward by this spring, and the valve 21 on to its seat; and the spring 30 is relatively small and weak to the spring 26, and it is under but slight initial stress, and it moves along with the valve stem 24, which follows the movement of the sleeve 25 when moved by the stronger spring 26.

25 The valve 21 is normally held upon its seat by the short upper end of the lever 2, and a lever 33 pivoted at 34 to the enlarged head 31 of the valve stem 24, the short arm of 33, resting on the outer end of the casing 27; and this arm 33 is held in this position, and so holds the spring 30 under compression or potential by means of the inner catch edge or detent 35, which engages the metal of the outer end of a slot formed in the arm 33.

30 This is the normal condition of the governor:

When the excessive speed referred to takes place, the detent or catch 35 is removed from the metal of the arm 33 it normally engages, and so frees the spring 26, which then forces down the sleeve 25 and so opens the valve 21; and it admits a fluid pressure from the source of pressure supply by way of the pipe 6 to the pipe 4, and so to the stop or controlling valve relay actuating apparatus or device 7, thereby closing the steam or motor fluid supply valve, and stops the engines.

To reopen the main stop or controlling valve, the parts have to be re-set by hand,

and the arm 33 moved so as to be engaged by the catch 35 of the lever 2.

In the modification shown in Fig. 3, the lever 2 which is actuated by the governor similarly as above described, is held in the 70 position to which it is moved temporarily, so that the apparatus is prevented from repeated actuations.

In this case, the lever 2 is connected directly to a jaw by a pin joint on the end of 75 the valve spindle 24, on the end of which the valve 21 is fixed, and which is moved off its seat 22 when the lever 2 is actuated by the protrusion of the bolt or moving device of the governor. Thus, as in the other arrangement, when the valve is open, fluid under pressure such as water, steam, compressed air or the like is allowed to pass to the underside of the valve 23 which controls the steam or motor fluid supply relay system; and in order to maintain the lever in the position in which the valve is opened, so that it will be clear of the protruded device of the governor—marked 17 in Fig. 2—there is fitted on the valve spindle 24 a 80 piston 24^x which is adapted to engage with a collar 37 on the valve spindle, the underside of the piston 24^x being open to the atmosphere by way of the port 38; while fluid under pressure has access to the top of the 85 piston 24^x by way of a port 39 leading from the valve stem guide to the underside of the valve 23.

90 By this piston acting on the collar 37 of the spindle, it tends to press the spindle 100 and valve in a direction which will maintain the lever 2 in the position in which its lower arm is clear of the protruding bolt of the governor.

95 In the bracket 41 of the casing 15 of the governor, there is a spring bolt marked 42, shown in dotted lines, and in the upper end of the arm 2 is a recess or hole 43, into which the spring pressed pin moves when the recess or hole 43 is over it, so that the lever 110 2 is detained against return movement after being operated by the governor, while at the same time it has a certain amount of freedom due to the hole or aperture 43 being such a size that the spring pressed bolt 115 will have a certain amount of play in the recess.

100 To reset the valvular device, the spring pressed pin 42 will be disengaged from the aperture 43, and the lever 2 moved to its 110 normal position; this being effected by the spring 30; and the valve 21 is brought back onto its seat again.

What is claimed is:—

1. In apparatus of the character described, a valve casing, a valve in the casing having a stem, a cylinder secured to the casing and having a port leading into the valve casing, a piston arranged upon the valve stem and slidably in the cylinder, a spring 125

to move the valve stem in one direction, and centrifugal means to move the valve stem in an opposite direction.

2. In apparatus of the character described, a valve casing, a valve in the casing having a stem, a cylinder arranged near the valve casing and having a port leading into the valve casing rearwardly of the valve, a piston mounted to slide in the cylinder and carried by the stem, and means to move the stem including a centrifugal governor.

3. In apparatus of the character described, a valve casing, a valve in the casing having a stem extending diagonally within the casing, a cylinder arranged diagonally of the casing and secured thereto and having a port which leads into the valve casing, said cylinder having the valve stem extending through and outwardly beyond the same, a piston carried by the valve stem and slideable within the cylinder, an element connected with the outer end of the valve stem, and a centrifugal governor to actuate the element.

25 4. In an engine motor fluid controlling system, a valve adapted to be opened by a connection actuated by the governor, a motor fluid controlling valve connected with the governor operated valve, and a pressure

service system connected with said valve, and means for temporarily retaining the governor actuated lever in the position in which it will not be repeatedly acted upon by the governor and is retained after it has been actuated.

5. In an engine motor fluid controlling system, a valve adapted to be opened by a connection actuated by the governor, a motor fluid controlling valve connected with the governor operated valve, a pressure service system connected with said valve, means for temporarily retaining the governor actuated lever in the position in which it will not be repeatedly acted upon by the governor, and a piston on the valve spindle adapted to be acted upon by pressure fluid when the valve is opened by fluid from the main service conduit, and to normally tend in a direction to maintain the valve in the open position.

In testimony whereof we have signed our names to this specification in the presence of two subscribing witnesses.
